UNITED STATES PATENT OFFICE.

STEPHEN KATKO, OF SHORING, PENNSYLVANIA, ASSIGNOR OF TWO-FIFTHS TO
EDWARD GOTTESMAN, OF BROWNSVILLE, PENNSYLVANIA.

LIFE-BOAT APPARATUS.

1,152,181.

Specification of Letters Patent. Patented Aug. 31, 1915.

Application filed May 12, 1915. Serial No. 27,518.

To all whom it may concern:

Be it known that I, STEPHEN KATKO, a subject of the King of Hungary, residing at Shoring, in the county of Washington 5 and State of Pennsylvania, have invented certain new and useful Improvements in Life-Boat Apparatus, of which the following is a specification.

This invention relates to new and useful 10 improvements in life boat apparatus.

The primary object of the invention is to provide a ready means for moving life boats along the deck of a vessel and then conveying the boats safely into the water 15 whenever desired for use.

A further object of the invention is to provide means for directing the positioning of life boats upon the deck of a vessel and means for receiving the boats and bodily 20 conveying the same to their launched positions upon the water adjacent the vessel and whenever desired.

It is also designed to provide a telescoping launching way fixed to the side of the vessel 25 and adapted for receiving a life boat carrying car and whereby the boat may be launched regardless of the depth of the draft of the vessel.

With these general objects in view and 30 others that will appear as the nature of the invention is better understood, the same consists in the novel combination and arrangement of parts hereinafter fully described, illustrated in the accompanying drawings 35 and pointed out in the appended claims.

In the drawings forming a part of this application and in which like designating characters refer to corresponding parts throughout the several views:—Figure 1 is 40 a top plan view of a vessel provided with the present device, the life boats and the railing being removed therefrom. Fig. 2 is a side elevation of the vessel showing a life boat in its launching position at the stern 45 thereof. Fig. 3 is an enlarged side elevation of the stern portion of the vessel partially broken away, the launched position of the car and boat being illustrated in dotted lines. Fig. 4 is a top plan thereof. Fig. 5 50 is a vertical sectional view through the launching way, a portion of a car being shown mounted thereon. Fig. 6 is a perspective view of the telescoping portion of the way sections, and Fig. 7 is a vertical

central sectional view of one of the turn 55 tables employed with the device.

The present device is herein illustrated in connection with a vessel 10 having its deck 11 provided with a track 12 positioned extending marginally therearound and adapted 60 for movingly supporting a desired number of life boats 13 of any convenient form, each of the boats having suitable traction wheels 14.

The track 12 is provided with turn tables 65 15 at as many points as desired, five being herein illustrated and one of which is positioned at the stern of the vessel. The form of these turn tables as best illustrated in Fig. 7, is of substantially the usual formation being provided with a track section 16 conforming to the gage of the deck track 12, while the table is centrally pivotally connected to the deck by means of a bolt 17 and is revolubly movable upon anti-friction 70 75 members 18.

A launching way 19 is obliquely mounted downwardly extending from the gunwale portion 20 of the vessel outwardly of each of the turn tables 15, a securing brace 21 connecting the same to the adjacent side of the vessel. The said ways 19 are of angle iron formation as best illustrated in Fig. 6 of the drawings, each of the same being provided with an outer extensible section 22 80 slidably mounted thereon and being formed of substantially L-shaped side members connected together by transverse bars 23, anti-friction members 24 being spaced between the inner flanges 25 of the said extension 85 90 sides and the adjacent underlying face of the way member.

A life boat supporting car 26 having a constantly horizontally positioned platform 27 is movably mounted upon each of the ways 95 19 by means of wheels 28, it being understood that the said car is of the general form usually employed with inclined-railways. The extensions 22 are each provided with a hoisting cable 29 secured to one of the cross 100 bars 23 thereof and operatively attached to a winding drum 30 upon the vessel and whereby the extensions 22 may be elevated or lowered for accommodating the way to the depth of the draft of the vessel and 105 whereby the extensions 22 may be properly positioned for placing their lower curved abutment ends 31 at its efficient distance be-

neath the surface of the water to allow for the submersion of the car 26 and its life boat 13, so that the boat will be placed in its launching position upon the water. A cord 5 32 is attached to each of the cars 26 and passes over a windlass 33 upon the deck of the vessel and whereby the car may be readily hoisted upwardly upon the launching way and allowed to travel down the same 10 by means of its own weight.

From this detailed description of the device, it will be seen that in the operation thereof, the life boats 13 are normally maintained upon the deck track 12 and when desired for launching, one of the same may be placed upon any one of the turn tables 15 and the adjacent gate 34 of the gunwale railing 35 may be opened and the turn table so adjusted as to position the track section 16 thereof in alinement with the platform 27 of the car 26 which is mounted upon the adjacent inclined launching way 19. The way extension 22 being lowered in the water, by means of the winding drum 30, the windlass 25 33 is released and the car 26 allowed to pass down the launching way until it reaches the end stop 31 of the extension 22 and in which position the boat 13 will be sufficiently submerged to be floated free of the car by reason of its buoyant position in the water. The cars 26 are provided with stop flanges 36 at their outer ends while similar stop flanges 37 are arranged at one of the ends 30 of the turn table track sections 16. With 35 the provision of the present arrangement, a large number of life boats filled with passengers may be quickly and safely launched over the side of the vessel and into the water, the entire device being readily attached to any vessel and consuming only slight space 40 thereon.

While the form of the invention herein shown and described is what is believed to be the preferred embodiment thereof, it is 45 nevertheless to be understood that minor

changes may be made in the form, proportion and details of construction without departing from the spirit and scope of the invention as set forth in the appended claims.

What is claimed as new is:—

1. Life boat apparatus for a vessel comprising a marginal boat track upon the deck thereof, track turn tables arranged within the deck track, railing gates at the edge of the deck adjacent the said turn tables, adjustable inclined ways positioned outwardly of the said gates and inclined-railway cars mounted upon the said ways and controlling cords for the said cars. 50 55

2. Life boat apparatus for a vessel comprising a marginal boat track upon the deck thereof, track turn tables arranged within the deck track, railing gates at the edge of the deck adjacent the said turn tables, inclined ways attached to the side of the vessel outwardly of the said gates, extensions slidably mounted upon the said ways having curved stops at the lower ends, cable hoisting means for the said extensions, and life boat cars mounted upon the said ways. 60 65 70

3. Life boat apparatus for a vessel comprising a marginal boat track upon the deck thereof, track turn tables arranged within the deck track, railing gates at the edge of the deck adjacent the said turn tables, inclined ways attached to the side of the vessel outwardly of the said gates, extensions slidably mounted upon the said ways having curved stops at the lower ends, cable hoisting means for the said extensions, cars having the walls thereof movably mounted upon the said ways and extensions and provided with a horizontal life boat receiving platform, a windlass for each of the cars mounted upon the deck of the vessel and a cord 75 80 85 carried by each windlass and attached to the adjacent car.

In testimony whereof I affix my signature.

STEPHEN KATKO.
